STORAGE TRAY FOR CIRCULAR KNITTING NEEDLE COMPONENTS

Robert W. Murphy, Morton Grove, and Cornelius Mark
Phipps, Wheaton, Ill., assignors to The Boye Needle
Company, Chicago, Ill., a corporation of Illinois

Filed July 29, 1965, Ser. No. 86,352

Term of patent 14 years

(Cl. D58—13)

FIG. 2

FIG. 3

FIG. 4

FIG. 5

FIG. 6

FIG. 7

FIG. 8

FIG. 9

FIG. 1 is a top plan view of a storage tray for circular knitting needle components embodying our new design, the bottom being a plane surface;

FIG. 2 is a side-elevational view thereof from the side 2-2 of FIG. 1, the opposite side being the same;

FIG. 3 is a side-elevational view thereof from the side 3-3 of FIG. 1, the opposite side being the same;

FIG. 4 is a sectional elevational view taken on the line 4-4 of FIG. 1;

FIG. 5 is a sectional elevational view taken on the line 5-5 of FIG. 1;

FIG. 6 is a sectional elevational view taken on the line 6-6 of FIG. 1;

FIG. 7 is a fragmentary sectional elevational view taken on the line 7-7 of FIG. 1;

FIG. 8 is a sectional elevational view taken on the line 8-8 of FIG. 1; and

FIG. 9 is a sectional elevational view taken on the line 9-9 of FIG. 1.

We claim:

The ornamental design for a storage tray for circular knitting needle components, as shown and described.
